UNITED STATES PATENT OFFICE

136,269

DESIGN FOR A BROOCH OR SIMILAR ARTICLE

Elsa Maria Kafka, New York, N. Y.

Application December 9, 1941, Serial No. 104,550

Term of patent 7 years

To all whom it may concern:

Be it known that I, Elsa Maria Kafka, a citizen of Austria, residing at New York, in the county of New York and State of New York, have invented a new, original, and ornamental design for a Brooch or Similar Article, of which the following is a specification, reference being had to the accompanying drawings, forming part thereof.

In the drawings

Fig. 1 is a front elevational view of the brooch or similar article, showing my new design.

Fig. 2 is a perspective side view thereof.

I claim:

The ornamental design for a brooch or similar article, as shown.

ELSA MARIA KAFKA.
